UNITED STATES PATENT OFFICE.

CHARLES POTTER, JR., OF PLAINFIELD, NEW JERSEY.

CUSHIONING DEVICE FOR PRINTING-MACHINES.

SPECIFICATION forming part of Letters Patent No. 358,568, dated March 1, 1887.

Application filed March 24, 1884. Serial No. 125,277. (No model.)

To all whom it may concern:

Be it known that I, CHARLES POTTER, Jr., of Plainfield, in the county of Union and State of New Jersey, have invented a new and useful Improvement in Cushioning Devices for Printing-Machines; and the following is declared to be a description of the same.

In printing-presses pistons are employed to compress the air in cylinders that are underneath the reciprocating type-bed, such compression serving to aid in stopping the momentum of the type-bed in one direction, and also aiding the first part of the movement in the other direction. Various devices have been employed to accomplish this purpose.

My invention relates to a device for accomplishing this object; and it consists in the combination, with the air-cushioning cylinder having a central partition, of a disk of leather, rubber, or other flexible material, and a spring-arm at each side of such partition. The spring-arms and flexible disks are secured to the central partition by a bolt, and said arms are bent outwardly and downwardly, and the lower end of each is slotted for the passage of a bolt, which also passes through the flexible disk, and said flexible disk is, by means of the spring-arm and bolt, kept in a normal position away from the central partition, so that the opening in the same allows the escape of air. These disks of flexible material act as valves for closing the opening in the central partition in opposite directions, preventing the escape of air whenever the speed of movement of the type-bed and the rush of air toward such valve is sufficient to overcome the spring and cause the valve to close. The confined air then acts as a cushion to overcome the momentum of the bed in stopping and starting the same.

In the drawings, Figure 1 is a longitudinal section of type-bed and cylinder, and Fig. 2 is a cross-section at the line *xx*.

The frame *A* of the printing-press and the pistons *B* may be of any desired shape or construction, and the type-bed *C* is provided with air-cushioning cylinders *D* beneath it. The center partition, *a*, between cylinders *D* has an opening for the passage of air from either side. The disks *b b'* are made of leather, rub-

ber, or other flexible material, and are secured to the partition *a* by a bolt or bolts, *c*. The spring-arms *d d'* are also secured to the partition *a* by the same bolt or bolts *c*, and washers *c'* may be employed under the heads of the bolt *c*.

The spring arms *d d'* are preferably made of the shape shown in Fig. 1, and their lower ends are slotted, and I employ bolts *e e'*, that are secured to the disks *b b'* and pass through the slots in the arms *d d'*, the object of said spring arms and bolts being to keep the disks *b b'* in a normal position away from the partition *a*, the arms, however, yielding to pressure.

The pressure exerted by the air within either of the cylinders *D* against the surface of the disk *b* or *b'* will be greater or less, according to the rate of speed at which the type-bed is traveling. The higher the speed the sooner the air will press the disk against the partition and close the escape of the air, and the greater the cushioning action, and vice versa. This cushioning action will be in proportion to the rate of speed of the reciprocating type-bed; hence the operation is automatic and very efficient. When the press is being turned slowly by hand, the rush of air will not be sufficient to overcome the spring of the valve; hence the valve will remain open and the air will not act as a cushion.

The cylinders may be attached to the frame and the pistons and rods to the bed, if desired, the valves and springs for each cylinder being made as before described and applied over the hole in the cylinder end.

I claim as my invention—

1. The combination, in a printing-press, with the stationary pistons and reciprocating type-bed, of air-cylinders beneath the bed, a partition between said cylinders, said partition having an opening therein, disks of flexible material, and spring-arms at each side of and secured to the partition, bolts connecting the disks and spring-arms, so that the spring-arms act to move the disks away from the partition, as and for the purposes set forth.

2. The combination, with the reciprocating type-bed in a printing-press, of a piston and an air-cushioning cylinder, there being an

opening in the partition or end of the cylinder, a disk within the cylinder covering the opening, a spring-arm, and a connection, substantially as described, between the end of the spring-arm and the disk, whereby the disk is drawn away by a yielding force that allows the disk to close the opening by an accumulated air-pressure, substantially as set forth.

Signed by me this 19th day of March, A. D. 1884.
